UNITED STATES PATENT OFFICE.

LEWIS S. PITCHER, OF ALBANY, NEW YORK, ASSIGNOR TO WILLIAM M. DUDGEON, EXECUTOR OF RICHARD DUDGEON, DECEASED.

HYDRAULIC JACK.

SPECIFICATION forming part of Letters Patent No. 706,850, dated August 12, 1902.

Application filed March 29, 1902. Serial No. 100,553. (No model.)

To all whom it may concern:

Be it known that I, LEWIS S. PITCHER, a citizen of the United States, and a resident of Albany, in the county of Albany and State of New York, have invented a certain new and useful Improvement in Hydraulic Jacks, of which the following is a full, clear, and exact description, reference being had to the accompanying drawings, in which—

10 Figure 1 illustrates a vertical sectional view of the parts embodying the invention. Fig. 2 illustrates a sectional view of the lowering-valve in its normal position. Fig. 3 shows a view the same as Fig. 2, the lowering-valve being forced off its seat, as during the act of lowering. Fig. 4 shows the lowering-valve when in its position of greatest depression, acting as a check to prevent accident. Fig. 5 shows a modified construction.

20 The purpose of this invention is to so construct the lowering-valve of hydraulic jacks as to preclude the possibility of accident or fracture of the load by ignorant or unskilful manipulation of the jack. Hydraulic jacks 25 are used under greatly differing circumstances and frequently in the hands of persons who do not understand the construction of a hydraulic jack nor the principles involved in their operation nor the danger to 30 the load carried by the jack nor the danger of serious accident, even involving loss of life, which may result from improper manipulation during the lowering operation, which is a much more hazardous proceeding than 35 that of lifting.

In the drawings hereof I have illustrated those parts only which are involved in the invention. It will be understood that the jack in question is supplied with the ordinary 40 pumping and lowering lever and that the piston of the pump is suitably connected therewith. These parts are so well understood that illustration or description thereof is not necessary.

45 Referring to the drawings, A illustrates the base of the jack; B, the cylinder; C, the ram; D, the pump-block; E, the pump-bore; F, the piston; G, the piston-valve; H, the bonnet for the piston-valve; I, the packing; J, the 50 lowering-valve block; K, the bonnet for the lowering-valve; L, the spring which normally

reseats the lowering-valve; M, the lowering-valve itself.

Referring now to Figs. 2, 3, and 4, the lowering-valve M is composed of three parts— 55 first, the valve proper, M'; second, the stem M'', reduced in area, so that the water may pass up its sides, and, third, the upper cylindrical part M', which fits snugly within the cylindrical boring M'', made in the bottom of the 60 pump-block D. Through the pump-block there are bored a series of openings N N, which connect with an opening O in the lowering-valve block, and thence through the bonnet L and the openings P therein to the 65 force-chamber Q of the jack. The arrangement and dimensions of these parts are such that when the lowering-valve is in the position shown in Fig. 2—that is to say, is against its seat R—no liquid can pass from the force- 70 chamber upwardly. Thus the load may be held permanently in its then position, whatever that may be. When it is desired to lower the load, the lever is manipulated in a manner well understood and the piston F de- 75 pressed until the bonnet H on its lower end presses against the upper end of the lowering-valve, as shown in Fig. 3, whereby it is depressed gradually and smoothly, so that the valve M' is forced off its seat sufficiently to 80 permit the liquid to escape from the force-chamber upwardly through the bonnet K, passing through the now open valve-seat R up- 85 wardly through the passage O and thence through the passages N N into the pump-bore and thence in a manner well understood back again to the reservoir in the head of the jack.

In the hands of a skilful operator the above- 90 stated depression of the piston and the forcing of the lowering-valve off its seat will be done with a strong firm slow movement, so that the lowering will be effected smoothly, easily, and continuously; but in the hands of an unskilled person the lowering is frequently effected by a strong sudden movement of the 95 pumping-lever, so that the lowering-valve is thrust off its seat quickly and to its fullest extent, whereby the liquid in the force-chamber is instantly released to its fullest capacity, which immediately results in a sharp de- 100 cline of the load attended by a violent jerky impulse being conveyed to the load and great

strain applied upon the jack. If the load be of a frangible nature, such as a locomotive or many forms of machinery, or if it have great inertia—such as a building, particularly of 5 brick or stone—then the vibration thus engendered almost inevitably results in the fracture of some part of the load and frequently in breakage of the jack itself, sometimes even resulting in loss of life. In order, therefore, 10 to prevent accident resulting from unskilful handling, I so construct the parts that if the above-stated excessive downward movement is suddenly applied to the plunger then the parts will be carried into the position shown 15 in Fig. 4, in which the lowering-valve is shown at its lowest position and in which the cylindrical part M^3 of the lowering-valve has passed clear across the mouths of the passages N N and effectually cut off the passage 20 of liquid through them, so that the lowering operation is arrested. Consequently in the hands of an ignorant or unskilful operator the sudden depression of the lowering-valve to its fullest extent can have no serious 25 results, because all that will happen will be a momentary shivering in the load during the time the part M^3 of the lowering-valve is passing the mouths of the passages N N . Thereupon the lowering action will at once 30 cease and opportunity will be given for a more skilful person to be called to the lever. Thus in many instances accident and fracture will be avoided.

In Fig. 5 I show a modified construction in 35 which the passages N connect with transverse passage N' , made in the lowering-valve block and which connect with the channel O . The advantage of this construction is that when the passages N connect diagonally with 40 the passage O their mouths necessarily have considerable vertical area, whereas if the transverse passages N' N' are employed the mouths are or may be of less vertical dimension. Thus the necessary transit of the lowering-valve, or, rather, the section M^3 thereof, to cut off the backflow of the liquid will be 45 greatly reduced.

It will be obvious to those who are familiar 50 with this art that modifications may be made in the details of construction of the parts without departing from the essentials of the invention. I therefore do not limit myself to such details.

Having described the invention, I claim—
55 1. In a hydraulic jack the combination of a ram provided with a passage-way connecting the force-chamber of the jack with the

bore of the pump, backflow-openings connecting the bore of the pump with the passage-way, a lowering-valve having an upper 60 part adapted to fit the passage-way and move through it to close the backflow-openings, the upper end of which valve extends into the bore of the pump sufficiently to enable the piston to depress the valve far enough to 65 close the backflow-passages, a reduced stem past which the liquid can flow, a valve-head below the reduced part of the stem and sufficient space below the head to permit the stated downward movement of the valve, for 70 the purpose set forth.

2. In a hydraulic jack the combination of a ram provided with a passage-way connecting the force-chamber of the jack with the bore of the pump, backflow-openings extending from the bore of the pump and connecting at substantially right angles with said passage-way, a lowering-valve having an upper part adapted to fit the passage-way and move through it to close the backflow-openings, the upper part of which valve extends into the bore of the pump sufficiently to enable the piston to depress the valve far enough to close the backflow-openings, 75 means for permitting the liquid to flow past the stem of the valve, a valve-head at the lower end of the valve and sufficient space below the head to permit the stated downward movement, for the purpose set forth.

3. In a hydraulic jack the combination of a ram provided with a passage-way connecting the force-chamber of the jack with the bore of the pump, backflow-openings connecting the bore of the pump with the passage-way, a lowering-valve having an upper 90 part which extends into the bore of the pump and which is adapted to fit the passage-way and move through it to close the backflow-openings, the upper end of which valve extends into the bore of the pump sufficiently 95 to enable it to be depressed far enough to close the backflow-passages, means for depressing the said valve, a reduced stem past which the liquid can flow, a valve-head below the reduced part of the stem and sufficient space below the head to permit the 100 stated downward movement of the valve, for the purpose set forth.

Signed at the city of New York this 26th day of March, 1902.

LEWIS S. PITCHER.
